Therapeutic Garment

Caroline A. Muller, Minneapolis, Minn.

Application July 22, 1942, Serial No. 451,835

4 Claims. (Cl. 2-27)

This invention relates to a garment or abdominal belt, and particularly to such a garment constructed and arranged to have a hygienic or therapeutic effect. The garment will also have the function of holding the figure of the wearer in desired shape or position.

Quite a few women are affected with fallen and collapsed organs. Many of these conditions are well recognized as definite ailments by the medical profession. Such ailments are often accompanied with considerable pain, especially when the patient must walk quite a little or be on her feet during her work.

It is an object of this invention to provide a comparatively simple and efficient garment provided with means for affording great relief in many ptosis conditions, and one which will correct the posture of the wearer and be very comfortable to wear.

It is a further object of the invention to provide a garment in the form of a corset, or abdominal belt having an adjustable opening at its front, in the rear of which is a panel provided with one or more stiffening means, such as stays, extending vertically therein to form a substantial backing together with one or more straps, one of which is disposed somewhat below the lower end of said stays, whereby said strap can be tightened against said stays giving the same an inward inclination so as to give an up-lift and supporting effect for the desired part of the body.

It is still another object of the invention to provide a garment such as above set forth, and one which has a smooth line over the hips so that the outer garments may be fitted thereover without unsightly bulges or lumps.

These and other objects and advantages of the invention will be fully set forth in the following description made in connection with the accompanying drawing in which like reference characters refer to similar parts throughout the several views and in which:

Fig. 1 is a view in front elevation of the garment;

Fig. 2 is a partial view in front elevation shown on an enlarged scale with some parts broken away and others omitted;

Fig. 3 is a horizontal section taken on line 3-3 of Fig. 2; and

Fig. 4 is a view in central vertical section showing somewhat diagrammatically the form of a pad used.

Referring to the drawing a garment is shown made from a sheet 10 of suitable fabric material,

the same being adapted to extend about and enclose the portion of the body adjacent the waist or abdomen. Said sheet preferably will have suitable hems 10a and 10b at its top and bottom and the same may be provided with vertically extending stiffening means or stays 11 circumferentially spaced thereabout. At the front portion thereof and at one side of the center of the garment the same is provided with a longitudinally extending opening 10c extending throughout the length thereof. Suitable fastening means 12 are secured to the edges of the garment at each side of the opening 10c and while these may be of any desired type which are quickly and easily engageable and disengageable, in the embodiment of the invention illustrated said fastening means include loops or eyelets 12a secured at one side of the opening and headed pins 12b. At the lower part of the garment, fastening means 13 are used at each side of opening 10c and while these also may be of any readily engageable and disengageable type, the same are illustrated as comprising loops or eyelets 13a and hooks 13b engageable therethrough. Said garment is also provided at its front and substantially centrally thereof with an opening 10d. The portions of the garment at each side of opening 10d are provided with eyelets 14 through which a lacing cord 15 extends. It will thus be seen that opening 10d is adjustable or may be varied in size by manipulation of cord 15. Extending across opening 10d in the rear of cord 15 and secured to the garment at either side of said opening is a panel 16 made of very flexible fabric material. While the length of this panel may be varied, in the embodiment of the invention illustrated it extends substantially from the band or hem 10a to a line spaced quite a distance from the bottom of the garment. Panel 16 will be provided centrally thereof with one or more stiffening means or stays. While in some cases one central stay is used, preferably and in the embodiment of the invention illustrated, two stays 17 are provided spaced a comparatively short distance apart. These stays extend from the top of panel 16 downwardly a considerable distance. The garment is also provided with a plurality of straps 18 extending across opening 10d. These straps have portions 18a secured to the garment at one side of said opening and provided with buckles 20. Buckles 20 are arranged so as to be disposed substantially at the center of opening 10d transversely thereof. Straps 18 have other portions 18b secured to the garment at the opposite side of opening 10d.

which will cooperate with buckles 20. Suitable keepers 21 are secured to the garment adjacent the ends of portions 18b and said portions will be disposed under or within said keepers. The lower ends of stays 17 terminate substantially at or just below the vertical center of the lower strap 18. It is customary to use a pad indicated as 22, with the garment, and this pad may take various shapes according to the ailment which is being treated. In the embodiment of the invention illustrated pad 22 is shown as having its bottom in a straight line or one plane and said bottom is substantially flush with the lower edge of the lower strap 18. The shape of the pad in vertical cross section is shown in Fig. 4. Pad 22 is of sufficient width to span opening 10d. The garment is preferably provided with straps 23 having suitable fasteners 24 thereon adapted to engage and support the hose of the wearer.

In operation, the garment will be placed about the body of the patient or wearer and fasteners 12 and 13 engaged. The straps 18 will be suitably placed to give the tightening effect on the garment where it is needed. The cord 15 will, of course, be adjusted to give the proper tension on the garment. The width of the opening 10d can thus be varied as desired. It is desired to have a lifting or supporting effect on the body, and this is accomplished by the straps 18 co-operating with the panel 16, and the stays 17. The panel with the stays 17 forms a backing having a proper area for supporting the body and preventing bulging or wrinkling of the skin or flesh as the garment is tightened. The lower strap 18 as described, extends below the lower end of the stays 17, and is tightened against said stays. This not only prevents the stays from projecting outwardly, but turns their lower ends inwardly thus giving a supporting or lifting effect. If a pad is used as is frequently the case, the panel 16 and the stays 17 act effectively to hold the pad and form a substantial backing therefor. When a pad is used, it will, of course, be of the proper shape for the particular ailment, and will be located to give the desired effect. The pad may be secured to panel 16. It will be noted that there are no openings or adjustments and no straps or buckles at the hip line or across the hip portion of the garment. The outer garments can thus be fitted smoothly and attractively over the hips and there are no objectionable lumps or bulges.

The garment has been amply tested in actual practice and has been found to be very successful and efficient. Applicant has worked with many physicians and these are enthusiastic about the results obtained. The garment has been effectively used to give relief in cases of backache, prolapsed kidneys, constipation, fallen womb, and other ptosis conditions. The garment is a great boon to women who are on their feet a great deal in their work. It greatly assists in obtaining a proper posture and this gives comfort and also relief from quite a few ailments.

From the above description it will be seen that I have provided a simple and efficient hygienic or therapeutic garment and one that can be used to give great relief in many cases of collapsed or fallen organs as well as other ailments. It has been used by a great many people who have found great comfort and relief in the wearing thereof.

It will, of course, be understood that various changes may be made in the form, details, arrangement and proportions of the parts, without departing from the scope of applicant's invention,

which generally stated, consists in a device capable of carrying out the objects above set forth, in the parts and combinations of parts disclosed and defined in the appended claims.

5 I claim:

1. A hygienic garment for supporting certain organs in the abdomen having in combination, a fabric sheet adapted to embrace the body adjacent the waist having an opening at its front

10 spaced from the center thereof, readily engageable and disengageable fastening means for connecting the parts of said sheet at each side of said opening, said garment having an opening substantially at its front central portion, means 15 for connecting the edges of said sheet adjacent said last mentioned opening and for varying the size of said opening, a fabric panel extending across said last mentioned opening in the rear of said last mentioned means, a pair of vertically spaced comparatively narrow straps extending across said last mentioned opening at an intermediate point therein and a stiffening means in said panel extending downwardly to substantially the center of the lower of said straps whereby 20 said panel and means will form a backing for a pad or the portion of the body disposed in the rear of said panel to properly distribute pressure thereon and said strap will press against the lower end of said means to give an uplifting effect.

2. A hygienic garment for supporting certain organs in the abdomen having in combination, a fabric sheet adapted to embrace the body adjacent the waist having an opening at its front

25 spaced from the center thereof, readily engageable and disengageable fastening means for connecting the parts of said sheet at each side of said opening, said garment having an opening substantially at its front central portion, means 30 for connecting the edges of said sheet adjacent

35 said last mentioned opening and for varying the size of said opening, a fabric panel extending across said last mentioned opening in the rear of said last mentioned means, stiffening means in said panel, a pair of vertically placed compara-

40 tively narrow straps secured to said sheet at each side of said last mentioned opening, the straps at one side of said opening having buckles thereon disposed substantially at the center of said opening aligned with said stiffening means and co-

45 operating with the straps at the opposite side of said opening.

3. A hygienic garment for supporting certain organs in the abdomen having in combination, a fabric sheet adapted to embrace the body adjacent

55 the waist, said garment having an opening substantially at its front central portion, means for connecting the edges of said sheet adjacent

60 said last mentioned opening and for varying the size of said opening, a fabric panel extending across said last mentioned opening in the rear of said last mentioned means, a pair of vertically spaced comparatively narrow straps spanning

65 said opening, and one or more stays in said panel substantially at the center thereof extending downwardly from its top to substantially the center of the lower of said straps, a pad disposed in the rear of said panel having its lower edge substantially in line with the lower edge of the lower of said straps whereby said stays will form

70 a backing for said pad and the ends of said stays may press against said lower strap and be pressed inwardly thereby.

4. A hygienic garment for supporting certain organs in the abdomen having in combination, a fabric sheet adapted to embrace the body ad-

Jacent the waist, said sheet extending smoothly over the hips and having a vertically extending opening at the front thereof, adjustable means connecting said sheet at the sides of said opening, a panel of flexible sheet material spanning said opening and secured to said sheet at the sides thereof, one or more stays at the central portion

of said panel extending downwardly from the top thereof to a line spaced from the bottom of said panel, and adjustable means spanning said opening and disposed just above the lower end of said stays to exert an inward inclination for giving a supporting effect.

CAROLINE A. MULLER.
